(57) **CLAIM**

The ornamental design for an electric washing machine as shown and described.

DESCRIPTION

1. Electric washing machine

1.1 : Perspective

1.2 : Front

1.3 : Back

1.4 : Left

1.5 : Top

1.6 : Bottom

1.7 : Reference view

The broken lines depict portions of the electric washing machine that form no part of the claimed design; this design has a lid made of transparent glass material, so the interior can be seen; reproduction 1.4 is a left view where the right view is a mirror image; reproduction 1.7 is a reference view showing the use state that the lid has been opened.

1 Claim, 7 Drawing Sheets
